HERMAN C. HIRSCHY, OF DULUTH, MINNESOTA, ASSIGNOR TO THE HIRSCHY COMPANY, OF DULUTH, MINNESOTA, A CORPORATION OF MINNESOTA

WASHING MACHINE

Application filed September 14, 1928. Serial No. 305,947.

In the operation of the agitator of a clothes washing machine, there is a tendency of the clothes to collect around the cone in the center of the tub, and when this occurs, the 5 clothes will be practically stationary, the agitation or movement thereof, being insufficient to force the water through the meshes of the garments and wash away the dirt. There is also a tendency in a machine of this 10 type, for a portion of the clothes in the tub to lie out near the wall of the tub with comparatively little motion, the result being the clothes do not have the desired travel and the washing operation is imperfectly or ineffectively performed.

The object therefore, of my present invention, is to provide an agitator for a washing machine which will not only tend to force the clothes outwardly away from the center of 20 the tub, but will insure sufficient travel or motion of the clothes to effectually force the water through the meshes and prevent any part of the clothes from stagnating between the fingers or blades of the agitator and the 25 wall of the tub.

A further object is to provide an agitator having a depending member with fingers or blades formed thereon which contact with the clothes at two or more points with substantially the same result that would follow from 30 depending the fingers of the hand into the clothes and then arranging to have the hand move back and forth and draw the clothes forward and backward, a space being provided 35 between the fingers through which the water may flow and through the fabric engaged by the fingers, the gap between the fingers allowing the water to pass between them and flow through the meshes of the garment 40 while the fingers on each side of the opening engage the garments and pull them back and forth as the disk supporting the fingers is reciprocated.

45 Other objects of the invention will appear from the following detailed description.

The invention consists generally in various constructions and combinations, all as hereinafter described, and particularly pointed 50 out in the claims.

In the accompanying drawings forming part of this specification,

Figure 1 is a sectional view of a tub and agitator embodying my invention;

Figure 2 is a bottom view of the agitator;

Figure 3 is a detailed sectional view showing the manner of mounting the agitator blade or hand upon the agitator disk;

Figure 4 is a detailed sectional view showing the engagement of the hand or blade fingers with the clothes in the operation of the machine;

Figure 5 is a detailed view showing one of the hands or blades removed from the agitator;

Figure 6 is a similar view showing a blade or hand with fingers of substantially the same length;

Figure 7 illustrates a blade with a series of three fingers thereon; and

Figure 8 is a detailed sectional view showing a blade or hand with three fingers in the act of pushing the clothes through the water as the agitator is reciprocated.

In the drawing, 2 represents a washing machine tub preferably of sheet metal. Any other suitable material, however, may be used in the construction of the tub, and it may of course be of any suitable size. Preferably it is of the form shown in the drawing, with an upper portion 3 having inwardly projecting walls overhanging the interior of the tub and providing an opening 4 which, when the device is in use, is closed by a suitable cover not shown. Within the tub I provide an upright standard 5 secured to the tub bottom by suitable means such as a lock nut 6 and an interiorly arranged flange not shown. A suitable stuffing box 7 is provided at the upper end of the standard, and a drive shaft 8 projects up through the standard and the stuffing box, and has an upper portion 9 rectangular substantially in cross section, at the base of which I preferably provide a circular flange 10. The driving shaft may be brought down through the top of the tub if preferred. A cone 11 encircles the lower portion of the drive shaft and is seated on the bottom of the tub, this cone forming the 100

subject matter of U. S. Patents #1,336,781 and #1,349,338. A block 12 has a socket 13 to receive the upper end of the drive shaft and shoulder 14 being formed in the walls of the socket to rest on the flange 10 and support the block for oscillation with the drive shaft, this shaft having a reciprocating oscillating movement to impart the desired stroke of the agitator. 15 represents a disk preferably of metal and 16 is a dome thereon overhanging the central opening 17 of the disk. A box 18 is centrally mounted on the dome and depends therefrom with parallel side walls adapted to snugly fit the correspondingly shaped walls of the block 12 and allow the disk or agitator to rise and fall in the operation of the machine and adjust itself vertically to the volume of clothes beneath it in the tub. When there is a considerable body of clothes in the tub, the agitator will be raised, and on the other hand, if there is only a small quantity of clothes being washed, then the agitator will automatically descend, accommodating itself to the volume of clothes beneath. A block 12 is preferably provided with a lifting finger piece 19 by means of which the agitator may be conveniently moved to place it in position in the tub or remove it therefrom. While the box 18 is free to rise and fall on the block 12 in the operation of the agitator, the walls will be at all times in contact with the block, and a rocking movement will be imparted to the agitator at all points in its vertical movement. Whenever desired, the agitator may be easily and quickly detached from the driving shaft by grasping the finger grip 19 and pulling upwardly thereon.

On the under side of the agitator disk, I provide a series of seats or holders for the agitator blades or hands. There are preferably 4 of these holders extending radially on the agitator disk, but this number may be varied if desired, and preferably these holders are equally spaced apart on the disk. As shown in Figures 1, 2 and 3, each holder comprises a radial recess 20 open at its inner end and having a depending wall 21 at the outer end forming a stop against which the blade or hand is seated, and held by centrifugal force when the agitator is in operation. Thus, as shown in Figure 1, when the agitator is in position for use, the wall of the cone will prevent each blade or hand from becoming separated from its holder, but when the agitator disk is raised sufficiently to clear the cone, then either one of the blades or hands can be conveniently removed. On opposite sides of each holder, I provide flanges 22 between which the head or upper portion of the hand or blade 23 is inserted. This head or upper portion has downwardly converging side walls and when the hand is inserted between the flanges and they are pressed inwardly to the position shown in

Figure 3, they will bear firmly against the surface of the head and hold it securely, but whenever desired, the flanges may be opened up or separated and allow the convenient removal of the hand from the agitator disk. 70 These hands or blades are preferably made of yielding resilient material, such as rubber, and I will now proceed to describe the depending or lower portion of each hand which forms the subject matter of my present invention. 75

As illustrated in Figure 1, each blade or hand has depending fingers 24 and 25 with a gap or opening 26 between them, both fingers being preferably inclined outwardly towards the wall of the tub with the fingers 25 depending below the finger 24, the lower portion of the finger 25 being outside preferably of the periphery of the agitator disk. 80

I have discovered in the operation of a washing machine, that the depending fingers of the agitator blade formed with a gap for the passage of water between them, will engage the clothes at two points as indicated in Figure 4, and will move them back and forth 85 through the water in much the same manner as the clothes would be moved if the operator placed his hand in the water and moved it back and forth with two of his fingers in engagement with the clothes, permitting the water to flow freely between the fingers and through the meshes of the clothes that are stretched between the fingers. The gap between the depending fingers allows freedom 90 of passage of the water, which, when the agitator blade is made solid, is retarded and must be pushed aside by the moving force of the agitator. In agitators of this kind as usually made, there is a tendency of the clothes to collect around the cone and be practically stagnant and there is also an area near the wall of the tub where the clothes are practically stationary. This is due, I believe, to the imperfect or retarded circulation of the water 95 through the clothes and around the blades as the agitator is reciprocated, due to the form or shape of the blades. 100

With my improvement, the clothes are held at two points and the free passage of the water between these two points insures a much better circulation through the clothes and the continued agitation of the clothes without any tendency to collect and stagnate around the walls of the cone or the outer walls of the tub. 105 The outer fingers, as shown, preferably depend below the inner ones and extend outwardly beyond the periphery of the tub to a point where the clothes will be engaged and agitated to such an extent that rapid and thorough cleansing will result. The fingers 110 being flexible preferably, will yield as the agitator is moved back and forth, and accommodate themselves to the pressure of the clothes thereon, bending slightly as the agitator encounters a mass of clothes, and then 115

returning to their normal position when the pressure is released.

In Figure 6, I have shown a slightly modified construction which consists in making the finger 24^a substantially the same length as the outer finger 25, leaving a gap between them as described with reference to the previous figure.

In Figures 7 and 8, I have shown two gaps, 26^a and 26^b, thus dividing the hand into three depending fingers, 27, 28 and 29. These fingers, as shown, are slightly narrower than those of the other views, but depend in substantially the same way and engage the clothes at three points instead of two, drawing them back and forth through the water and causing it to flow freely through the meshes of the clothes and through the gaps between the fingers. These fingers also yield under pressure in substantially the same way as described with reference to the hand with two fingers.

I have found in operating this agitator with the handlike blades engaging the clothes at a plurality of points, in a manner similar to the separated fingers of the hand, that currents of water will flow through the gaps between the points of contact with the clothes and establish a circulation in the tub through the meshes of the clothes and thoroughly and quickly cleanse the garments. The water, instead of being pushed ahead of the clothes and displaced by the oscillating blades, which is done when the blades are made solid and imperforate, will flow freely through the gaps between the fingers, passing rapidly through the clothes which are stretched across the gaps and held by the fingers on each side.

The blades instead of having gaps separating them into depending fingers, may have openings therethrough to allow freedom of passage of the water as the blades are oscillated. This arrangement will obtain the desired result to a certain degree, but I prefer to extend the openings or gaps through the lower edge of each blade so that independent clothes engaging fingers will be provided.

It will be understood from the foregoing that these blades or hands may be mounted in any suitable way on the under side of the agitator disk, there may be any suitable number of the blades arranged in any preferred distance apart, and while I prefer blades with two depending fingers formed substantially as shown in the drawing, I do not confine myself to this number, and though I prefer to use rubber in the manufacture of the blades or hands, any other suitable material may be employed and still be within the scope of my invention.

An important function of applicant's invention is to prevent inward travel of the clothes during washing operation and collection thereof around the core or center hub or operating shaft. This function is obtained

partly by forming the fingers of compressible and resilient material, partly by spacing the fingers in a radial direction, partly by making the outermost fingers longer than the inner fingers and partly by slanting at least the outermost finger outwardly and downwardly.

I claim as my invention:

1. A washing machine agitator having pairs of depending fingers, those of the same pair being in substantially the same vertical plane, an opening being provided between the fingers of each pair, the clothes being engaged by said fingers and stretched across said opening to force water through the clothes and said opening when said agitator is oscillated.

2. A washing machine agitator having handlike blades depending therefrom radially at intervals around a central axis, each of said blades having depending fingers with a gap between them, the outer finger of each blade being longer than the inner one and projecting diagonally outside the periphery of said agitator.

3. A washing machine agitator and handlike blades depending therefrom, said blades being composed of yielding resilient material, each blade having a comparatively long finger depending obliquely therefrom, with a gap or opening separating said finger from the remaining portion of the blade, said finger engaging the clothes during the oscillating movement of the agitator, the water flowing through the opening in said blade during such movement.

4. A washing machine agitator having an inner and an outer group of fingers depending therefrom, the clothes being engaged by said inner and outer fingers and moved through the water as the agitator is operated, said fingers being adapted to yield under pressure of the clothes, and having a gap or opening between them for freedom of passage of the water.

5. A washing machine agitator having on the under side thereof a series of radially arranged holders, blades having heads to fit within said holders and be supported thereby, each blade having its lower portion divided vertically to form depending fingers between which the clothes are stretched and the water forced therethrough when said agitator is oscillated.

6. A washing machine agitator having a series of radially arranged holders on the under side thereof, flat blades composed of rubber having heads to fit within said holders and supported thereby, each blade having a pair of depending fingers formed thereon with a gap between them, said fingers being adapted to engage the clothes at two points and move them through the water while stretched across the gap between said fingers, for the purpose specified.

7. A washing machine agitator having fingers of compressible resilient material de-

pending therefrom, with gaps or openings between them, said fingers being adapted to engage the clothes as said agitator is oscillated, the engagement of said fingers with the clothes stretching them across said gap and causing the water to flow rapidly through the meshes of the clothes as the agitator is oscillated.

8. A washing machine agitator having a plurality of groups of paddle-like fingers, the members of which are spaced radially with respect to the axis of rotation of the agitator, said fingers being composed of compressible and flexible material.

10 9. A washing machine agitator having a plurality of groups of paddle-like fingers, the members of which are spaced radially with respect to the axis of rotation of the agitator, the broadest surfaces of said paddle-like fingers being faced in direction of rotation.

15 10. A washing machine agitator having a plurality of depending fingers of compressible and flexible material arranged in groups, the members of each group being spaced apart substantially radially with respect to the axis of rotation of the agitator, said fingers being slanted outwardly and downwardly.

20 11. A washing machine agitator having a plurality of depending fingers of compressible and flexible material arranged in groups, the members of each group being spaced apart substantially radially with respect to the axis of rotation of the agitator, the outermost fingers being longer than the innermost.

25 12. In a washing machine, a washing chamber, a washer shaft, a dolly connected for operation by said shaft, and having a plurality of depending fingers of compressible and flexible material, arranged in groups, the members of each group being spaced apart substantially radially with respect to the shaft.

30 13. In a washing machine a washing chamber, a washer shaft, a dolly connected for operation by said shaft, and having a plurality of depending fingers of compressible and flexible material, arranged in groups, the members of each group being spaced apart substantially radially with respect to the shaft, the outermost fingers being longer than the innermost.

35 14. In a washing machine including a washing chamber, a washer shaft, a dolly connected for operation by said shaft, and having a plurality of depending fingers of compressible and flexible material arranged in groups, the members of each group being spaced apart substantially radially with respect to the shaft, said fingers being slanted outwardly and downwardly.

40 15. In a washing machine including a washing chamber, a washer shaft, a dolly connected for operation by said shaft, and having a plurality of depending fingers of compressible and flexible material arranged in groups, the members of each group being spaced

apart substantially radially with respect to the shaft, and the horizontal radial dimension of each finger being greater than the distance between the fingers.

5 In witness whereof, I have hereunto set 70
my hand this 8th day of September, 1928.
HERMAN C. HIRSCHY.
